UNITED STATES PATENT OFFICE.

CHARLES S. BONNEY, OF PHILADELPHIA, PENNSYLVANIA.

IMPROVEMENT IN SAW-FILING VISES.

Specification forming part of Letters Patent No. **135,883**, dated February 18, 1873.

To all whom it may concern:

Be it known that I, CHARLES S. BONNEY, of the city and county of Philadelphia, in the State of Pennsylvania, have invented certain Improvements in Saw-Filing Vises, of which the following is a specification:

The nature and object of the invention is to produce a vise for holding saws, while being filed, much more firmly than the ordinary saw-filing vise, thereby preventing much of the noise and trembling of the same, and consequent wearing of the file.

In the following description, Figure 1 is a perspective view of the vise complete. Fig. 2 is the movable jaw detached. Fig. 3 is the eccentric lever.

A is the back or stationary jaw, to which are attached the two arms C C, which extend down to the curves D D and thence up to E E. B is the front or movable jaw, to which are attached the arm F, the cross-piece G, and the two screws H H, and which is supported in

position by the cross-bar G, resting in the curves D D, where it can rock sufficiently to allow the opening and closing of the jaws. J is an eccentric lever, which works in the end of the arms C C at E E, and which closes the vise by a downward movement of the same, the vise being so constructed that it will open itself when the lever is raised. The trembling of the saw is prevented by turning the screws H H against the saw, so as to spring the same sufficiently for the purpose.

Claim.

I claim—

The adjustable screws H H, in combination with the jaws A B for springing the saw to any desired amount to prevent the trembling of the same.

CHARLES S. BONNEY.
